CLAIM

The ornamental design for a headset for communication, as shown and described.

DESCRIPTION

FIG. 1 is a perspective view of the embodiment of the headset for communication.

FIG. 2 is a front view thereof.

FIG. 3 is a back view thereof.

FIG. 4 is a left view thereof.

FIG. 5 is a right view thereof.

FIG. 6 is a top view thereof.

FIG. 7 is a bottom view thereof.

FIG. 8 is another perspective view of the embodiment of the headset for communication.

FIG. 9 is a front view thereof.

FIG. 10 is a back view thereof.

FIG. 11 is a left view thereof.

FIG. 12 is a right view thereof.

FIG. 13 is a top view thereof; and,

FIG. 14 is a bottom view thereof.

The features shown in broken lines depict environmental subject matter only and form no part of the claimed design.

1 Claim, 14 Drawing Sheets
